CLAIM

The ornamental design for a medical injector, as shown and described.

DESCRIPTION

FIG. 1 is a rear perspective view of a medical injector in an initial state, in accordance with an embodiment of the present design;

FIG. 2 is a front perspective view thereof in the initial state;

FIG. 3 is a top plan view thereof in the initial state;

FIG. 4 is a bottom plan view thereof in the initial state;

FIG. 5 is a right side elevation view thereof in the initial state;

FIG. 6 is a left side elevation view thereof in the initial state;

FIG. 7 is rear elevation view thereof in the initial state;

FIG. 8 is a front elevation view thereof in the initial state;

FIG. 9 is a rear perspective view of the medical injector of

FIG. 1 in an intermediate state;

FIG. 10 is a front perspective view thereof in the intermediate state;

FIG. 11 is a top plan view thereof in the intermediate state;

FIG. 12 is a bottom plan view thereof in the intermediate state;

FIG. 13 is a right side elevation view thereof in the intermediate state;

FIG. 14 is a left side elevation view thereof in the intermediate state;

FIG. 15 is rear elevation view thereof in the intermediate state;

FIG. 16 is a front elevation view thereof in the intermediate state;

FIG. 17 is a rear perspective view of the medical injector of

FIG. 1 in a final state;

FIG. 18 is a front perspective view thereof in the final state;

FIG. 19 is a top plan view thereof in the final state;

FIG. 20 is a rear elevation view thereof in the final state;

FIG. 21 is a right side elevation view thereof in the final state;

FIG. 22 is a left side elevation view thereof in the final state;

FIG. 23 is rear elevation view thereof in the final state;

(Continued)

FIG. 24 is a front elevation view thereof in the final state; FIG. 25 is a rear perspective view of another embodiment of a medical injector in an intermediate state, in accordance with the present design;

FIG. 26 is a front perspective view thereof in the intermediate state:

FIG. 27 is a top plan view thereof in the intermediate state; FIG. 28 is a bottom plan view thereof in the intermediate state;

FIG. 29 is a right side elevation view thereof in the intermediate state;

FIG. 30 is a left side elevation view thereof in the intermediate state;

FIG. 31 is rear elevation view thereof in the intermediate state;

FIG. 32 is a front elevation view thereof in the intermediate

FIG. 33 is a rear perspective view of another embodiment of a medical injector in an intermediate state, in accordance with the present design.

FIG. 34 is a front perspective view thereof in the intermediate state;

FIG. 35 is a top plan view thereof in the intermediate state; FIG. 36 is a bottom plan view thereof in the intermediate

FIG. 37 is a right side elevation view thereof in the inter-

FIG. 37 is a right side elevation view thereof in the intermediate state;

FIG. 38 is a left side elevation view thereof in the intermediate state;
FIG. 39 is rear elevation view thereof in the intermediate

FIG. 39 is rear elevation view thereof in the intermediate state; and,

Portions of the medical injector shown in dashed lines in

Portions of the medical injector shown in dashed lines in FIGS. 1-4, 8-12, 16-20, 24-28, 32-36, and 40 depict unclaimed portions of the medical injector that are included for environmental purposes only.

1 Claim, 20 Drawing Sheets
